UNITED STATES PATENT OFFICE.

CHARLES MEHLIN, OF FORT LEE, NEW JERSEY.

FALL-BOARD FOR UPRIGHT PIANOS.

1,077,732.

Specification of Letters Patent.

Patented Nov. 4, 1913.

Application filed December 10, 1912. Serial No. 735,979.

To all whom it may concern:

Be it known that I, CHARLES MEHLIN, a citizen of the United States, residing in Fort Lee, in the county of Bergen, in the State of New Jersey, have invented certain new and useful Improvements in Fall-Boards for Upright Pianos, of which the following is a specification, reference being had to the accompanying drawing, which 10 forms a part hereof.

This invention relates to fall-boards particularly designed for use in connection with upright pianos.

It has for an object to provide a fall-board which, when in closed position, will present a broad plane surface where hitherto the exterior faces of the front and rear falls have formed a cover having surfaces in two planes.

20 A further object is to provide a fall-board which may be more readily secured to or removed from the arms of the piano which support it, than is possible in present constructions.

25 A further object is to form the front and rear folds so they may be connected by invisible hinges, thus improving further the general appearance of the entire cover, and may be moved to open and closed position 30 more easily than heretofore.

Still another object is to remove the objections hitherto raised to the two-fold type of fall-board by reason of the open joint between the front and rear portions, by 35 forming their contiguous edges in a manner to insure a tight connection when the cover is closed.

The invention will be more particularly described hereinafter with reference to the 40 accompanying drawing in which—

Figure 1 is a view in perspective of an upright piano provided with a fall-board constructed in accordance with the present invention. Fig. 2 is a sectional view on an 45 enlarged scale of a fall-board constructed in accordance with the present invention, the pivotal supports therefor being shown in end elevation. Fig. 3 is a fragmentary view in detail showing a hinge connection 50 between the front and rear folds of the improved fall-board, the latter being in closed position. Fig. 4 is a similar view showing the two folds in angular relationship. Fig. 55 is a fragmentary plan view showing in detail the means for supporting removably the fall-board on the arm of the piano.

Fig. 6 is a view in front elevation of the same.

As this description proceeds, it will be evident to those skilled in the art that fall-boards constructed in accordance with this invention are applicable largely, if not entirely to upright pianos and as illustrated in Fig. 1 an improved board applied to that type of piano is herein shown.

The fall-board comprises a front fall or lid *a* of any approved shape and preferably provided with a depending portion adjacent its forward edge whereby the front edges of the piano keys are completely incased. Adjacent the rear edge of the front fold *a* is formed a rabbeted portion *a'* which receives the forward edge of the rear fall or lid *b*. Projecting downwardly from the base of the rabbeted portion *a'* of the front fall *a*, is a transverse flange *a''*, the lowermost portion of which is disposed in juxtaposition to the keys of the piano and may be provided with a strip of felt or other suitable material, to contact with and limit the 80 lifting movement of the keys when the fall-board is in open position.

The rear fall *b*, as before stated, has its forward edge resting in the rabbeted portion *a'* of the front fall *a* and is preferably 85 of a thickness equal to the height of said rabbeted portion so that its upper surface lies in the same plane with the upper surface of the front fold *a* and forms therewith a fall-board which, in closed position, 90 has a broad flat top. The rear fall *b* is preferably hinged to the front fold *a* by means of invisible hinges indicated at *c*. As illustrated more particularly in Figs. 3 and 4 these hinges may be mounted on 95 suitable plates *c'* set in corresponding opposed recesses in the contiguous edges of the front and rear folds *a* and *b*. Adjacent the rear edge of the rear fall *b* is formed a depending rail section *b'* preferably faced 100 with a strip *b''* of any suitable soft material, which engages supporting and guide blocks *d* secured to the arms of the piano, all of which structure may be generally similar to that hitherto employed.

Set in one end face of the key slip *a''* is a suitable bracket *e* having a forked portion *e'* to receive a stud *f* mounted on the inner face of the adjacent arm. In the branches of the forked portion *e'* of the 110 bracket *e* are interiorly threaded recesses adapted to receive a correspondingly

threaded stud g for a purpose which will presently appear. The opposite end face of the key rail a^2 may be provided with a recess adapted to receive a corresponding stud mounted on the inner face of the adjacent arm. This construction is commonly used and it has not been thought necessary to illustrate it herein.

From the description above given, it will be understood that in mounting the fall-board in position, the single stud on one end face of the fall-board is inserted in its corresponding recess, as described, and that the fall-board is then moved so that the forked branches of the bracket e will receive the stud f carried by the opposite end board of the piano. When the stud f is in position the threaded stud g may be screwed home through the branches of the bracket e to hold the forked bracket on the stud.

As shown particularly in Fig. 2 the bracket e has its forked end e' so disposed with respect to the key rail a^2 and the rear fall b so that the head of the threaded stud g is readily accessible when the rear fall b is folded forward on the front fall a . In mounting and removing the fall-board it will be necessary to place the two falls in this position and to have the usual top frame of the piano removed in order that, after the stud f is secured in place in the forked bracket e , the rear fold b may be moved rearwardly on its hinges to its normal position. A threaded stud f' may be disposed in the end face of the key rail a^2 and in alignment with the stud f so that the latter bears thereon and by suitable adjustment of the threaded stud, longitudinal movement of the cover is prevented.

By resting the forward edge of the rear fall b in the rabbeted portion a' of the front fall a and by securing the two falls together with the general type of invisible hinge e herein described, it will be evident that when the front fall is displaced from its closed position, the initial movement of the forward portion of the rear fold will be upward. By inclining rearwardly the upper edge of the supporting blocks d from the forward edge thereof and by throwing the center of gravity of the rear fall b upwardly

as just pointed out, the continued movement of the rear fold to its rearmost position may be occasioned by the application of less pressure than must be employed in constructions now generally used. Likewise, the stress on the various parts is correspondingly reduced and a more desirable operation of all of the parts from closed to open position is obtained. It will further appear that by disposing the forward edge of the rear fold b in the rabbeted portion a' and by using the invisible hinges e of the general type herein illustrated, thus permitting a very close junction over a relatively great area of the contiguous edges of the falls, a much closer joint is effected between the two than has hitherto been obtained in fall-boards of this type and no hinge is visible when open or closed.

Modifications of the fall-board herein illustrated and of the auxiliary devices used in the mounting thereof will suggest themselves to those skilled in the art but all such changes are to be considered within the scope of this invention, provided they fall within the terms of the claims hereunto appended.

What I claim is:—

1. A fall-board for pianos comprising a front fall, a rear fall hinged thereto, a forked bracket mounted in the end face of said front fall and opening rearwardly, a supporting stud carried by the piano and adapted to engage said bracket and removable means to close said fork in rear of the stud.

2. A fall-board for pianos comprising a front fall, a rear fall hinged thereto, a bracket set in the end face of the front fall and having a forked portion opening rearwardly, a supporting stud mounted on the piano and adapted to be embraced by the forked portion of the bracket and a threaded stud to close the forked bracket in the rear of the stud and accessible from above.

This specification signed and witnessed this 4th day of December A. D., 1912.

CHARLES MEHLIN.
